UNITED STATES PATENT OFFICE.

THOMAS J. WILSON, OF STEPHENVILLE, TEXAS.

DESIGN FOR AN ANT-TRAP.

SPECIFICATION forming part of Design No. 34,927, dated August 13, 1901.

Application filed July 8, 1901. Serial No. 67,554. Term of patent 7 years.

To all whom it may concern:

Be it known that I, THOMAS JEFFERSON WILSON, a citizen of the United States, residing at and whose post-office address is 5 Stephenville, in the county of Erath and State of Texas, have invented and produced a new and original Design for Ant-Traps, of which the following is a specification, reference being had to the accompanying drawings, forming a part hereof.

Figure 1 is a plan view of an ant-trap, showing the new design. Fig. 2 is a side elevation of the same. Fig. 3 is a central longitudinal section therethrough.

15 The ant-trap comprises a tray-shaped structure 1, connected with a cylindrical receptacle 2 by an interposed tubular connection 3, the said tubular connection bearing a radial relation to both the tray and the receptacle 2. The tray 1 comprises a disk-shaped bottom 4 and an annular top 5, composed of reversely-inclined inner and outer walls 6 and 7, respectively, the outer wall meeting the peripheral edge of the bottom 4, while the inner edge of the inner wall 6 is extended downward in the form of a pendent annular mouth 8, which extends below the plane of the bottom 4. On the line where the inner and outer walls 6 and 7 converge an annular entrance 9 is left, said entrance being bounded at opposite sides by inwardly and downwardly turned flanges or ribs 10. The receptacle 2, which is of cylindrical form, is closed

by a bottom 11 and provided at the top with an annular flange 12, of ogee shape in cross-section, as shown in Fig. 3, the inner edge being turned downward, as shown at 13. The tubular connection is made tapering, being small where it unites with the receptacle 2. Said receptacle is formed in one side with 40 an opening 14, with which the tubular connection 3 communicates, and the receptacle is also provided with an internal ledge or shelf 15, terminating in a downwardly - inclined lip 16.

45 The leading or material feature of the design consists in the circular tray connected with the cylindrical receptacle by means of a radially-disposed connection, and another important feature of the design resides in 50 providing the tray with a top comprising reversely-inclined inner and outer walls, the inner wall terminating in a centrally-disposed pendent mouth which projects below the plane of the bottom of the tray.

55 Having described my invention, what I desire to secure by Letters Patent is—

The design for an ant-trap as herein shown and described.

In testimony whereof I affix my signature 60 in presence of two witnesses.

THOMAS J. WILSON.
